UNITED STATES PATENT OFFICE.

JULIUS W. McAFFEE, OF CHICAGO, ILLINOIS, ASSIGNOR TO STANDARD VARNISH WORKS, OF CHICAGO, ILLINOIS, A CORPORATION OF NEW YORK AND ILLINOIS.

DRYING-ROOM.

1,071,449.

Specification of Letters Patent. Patented Aug. 26, 1913.

Application filed March 17, 1913. Serial No. 754,811.

To all whom it may concern:

Be it known that I, JULIUS W. McAFFEE, a citizen of the United States, and a resident of the city of Chicago, county of Cook, 5 and State of Illinois, have invented certain new and useful Improvements in Drying-Rooms, of which the following is a specification.

My invention relates to improvements in 10 drying rooms especially adapted for use in drying fillers, stains, varnishes, enamels and kindred liquid and pigment products, the object of the invention being to provide an improved drying room of this character 15 which is provided with improved means for inducing circulation therein.

The invention consists in the combinations and arrangements of parts hereinafter described and claimed.

20 The invention will be best understood by reference to the accompanying drawing forming a part of this specification and which is a perspective view of a drying room embodying my invention, shown partially in section.

The preferred form of construction as illustrated in the drawing comprises a room made in any suitable or desired manner and provided at each side and near the bottom 30 thereof with a heating coil 1. A suitable supply pipe 2 leads to the top of one of said coils and a suitable discharge pipe 3 leads from the bottom of each of said coils, the tops of said coils being connected by 35 means of a pipe 4 extending across the back of the room, this arrangement being provided so as to permit of the circulation of hot water or other heating medium through said coils.

40 A cooling coil 5 is arranged centrally in the room adjacent the top thereof, as shown, and is provided with a suitable drip pan 5'. A suitable supply pipe 6 and a discharge pipe 7 are connected with coil 5 to permit 45 of the circulation of cold water or other cooling medium through coil 5. A shield wall 8 is arranged adjacent each of the coils 1 and a little above the floor of the room and terminating below the ceiling thereof 50 so as to form an air duct about each coil to induce upward circulation of air from

said coil. Curved deflectors 9 are arranged in the upper corners of the room to facilitate the circulation of air therethrough. By this arrangement, it will be observed that 55 two air circulations will be induced in the room, by the combined action of the heating and cooling coils. The hot air arising from each coil being cooled adjacent the ceiling by the cooling coils 5 and 6, said 60 cooled air falling in the room thus effecting a double circulation, as indicated by the arrows. The articles to be dried are arranged in the room in any suitable or desired manner, as will be readily understood 65 by those skilled in the art.

While I have illustrated and described the preferred form of construction for carrying my invention into effect, this is capable of variation and modification without 70 departing from the spirit of the invention. I, therefore, do not wish to be limited to the precise details of construction set forth, but desire to avail myself of such variations and modifications as come within the scope 75 of the appended claims.

Having described my invention what I claim as new and desire to secure by Letters Patent is:

1. The combination in a drying room, of 80 heating means arranged at each side thereof near the bottom; and cooling means arranged substantially centrally and near the top thereof, substantially as described.

2. The combination in a drying room, of 85 a heating coil arranged at each side near the bottom thereof; and a cooling coil arranged substantially centrally and near the top thereof, substantially as described.

3. The combination in a drying room, of 90 a heating coil arranged at each side near the bottom thereof; a cooling coil arranged substantially centrally and near the top thereof; and a shield wall arranged adjacent each of said side coils and forming an 95 air duct therefor open at both top and bottom, substantially as described.

4. The combination in a drying room, of 100 a heating coil arranged at each side near the bottom thereof; a cooling coil arranged substantially centrally and near the top thereof; a shield wall arranged adjacent each of

said side coils and forming an air duct therefor open at both top and bottom; and deflectors arranged in the upper corners of the room and adapted to facilitate circulation of air therein, substantially as described.

In testimony whereof I have signed my

name to this specification in the presence of two subscribing witnesses.

JULIUS W. McAfee.
